SWITCH & SIGNAL COMPANY, OF SWISSVALE, PENNSYLVANIA, A CORPORA-
TION OF PENNSYLVANIA.

THREE-POSITION RELAY.

1,416,953.

Specification of Letters Patent. Patented May 23, 1922.

Application filed June 26, 1919. Serial No. 306,807.

To all whom it may concern:

Be it known that I, ROBERT M. GILSON, a citizen of the United States, residing at Pittsburgh, in the county of Allegheny and State of Pennsylvania, have invented certain new and useful Improvements in Three-Position Relays, of which the following is a specification.

My invention relates to three-position electrical relays, and particularly to relays of this type comprising a contact-operating member movable in opposite directions from an intermediate position to two extreme positions.

I will describe one form of relay embodying my invention, and will then point out the novel features thereof in claims.

In the accompanying drawings, Fig. 1 is a view showing in side elevation the operating parts of one form of relay embodying my invention. Fig. 2 is a top view of part of the relay shown in Fig. 1, and illustrating particularly the means for moving the contact-operating member of the relay.

Similar reference characters refer to similar parts in each of the views.

Referring first to Fig. 1, the reference character B designates a base plate which supports all of the other parts of the relay. Pivottally mounted at the point 2 is a vane V of non-magnetic, electro-conductive material such as aluminum, which vane constitutes the movable contact-operating member of the relay. The vane V is biased to an intermediate position, this being the position in which it is shown in the drawing, but it may be moved in the direction indicated by the arrow a to an upper extreme position, and in the direction indicated by the arrow b to a lower extreme position, these movements being accomplished by means hereinafter explained.

The vane V is biased by its own weight to move from its upper extreme position to its lower extreme position. The biasing force tending to swing the vane from its lower extreme position to the intermediate position is produced by a counterweight comprising a rod 3 pivotally mounted at 3^a and carrying a weight W. The downward movement of this counterweight is limited by a screw 7 which passes through the weight W and rests on the base plate B. The counterweight is connected with the vane by a link 4 the up-

per end of which is pivotally connected to a crank 5 attached to the vane. The lower end of the link 4 is provided with a slot 4^a through which passes a pin 6 carried by the counterweight rod 3. The parts are so adjusted that when the vane V is in its intermediate position and screw 7 is resting on the base plate, the pin 6 is at the lower end of the slot 4^a. It follows, then, that if the vane is moved from its intermediate position in the direction of arrow b, weight W is raised; and that when the force thus acting on the vane is removed the vane will be returned to its intermediate position. The vane is free to swing upwardly from its intermediate position without interference by the counterweight because of the slot 4^a in link 4.

In order to provide for adjustment of the torque exerted on the vane by the counterweight, the rod 3 is preferably extended to the left of the pivotal point 3^a and threaded to receive nuts 8.

The contact apparatus controlled by the vane V comprises a rocker 10 pivotally mounted at 10^a and provided with an operating arm 13 which is connected with the crank 5 by a link 9. The rocker 10 carries two contact members 11 and 12 which engage with two fixed contact members 11^a and 12^a respectively. The parts are so adjusted that when the vane occupies its intermediate position, both contacts 11-11^a and 12-12^a are open; that when the vane is swung upwardly from this position, contact 11-11^a becomes closed; and that when the vane is swung downwardly from its intermediate position, contact 12-12^a becomes closed.

The vane V may be moved in opposition to its biasing forces by any suitable means. This means, as here shown, comprises two U-shaped cores 14 and 14^a of magnetizable material mounted on opposite sides of the vane with the pole-pieces of one core confronting those of the other (see Figs. 1 and 2), and a third core 15 of similar material arranged with its pole-pieces on opposite sides of the vane and between the pole-pieces of the cores 14 and 14^a. The cores 14 and 14^a are provided with coils L and L^a which are usually connected in series, and core 15 is provided with a coil T. If the three coils are supplied with alternating currents, it

will be seen that the vane is traversed by one magnetic flux due to coil T, and by two magnetic fluxes, one on each side of the first, due to coils L, L^a. If the current in coils L and L^a is displaced in phase from the current in coil T, the two currents being of the same frequency, a torque is exerted on vane V tending to swing it up or down, and this torque may be reversed by reversing the polarity of the current in coil T. Of course, if the supply of current to coil T, or to coils L, L^a, is discontinued, the torque produced by the cores is entirely removed.

15 The relay shown in the present application is particularly well adapted for use as a track relay in railway signaling systems, in which instance the coil T may be supplied with current from a track circuit the 20 polarity of which is reversible, and the coils L, L^a may be supplied with current directly from a transmission line.

When the vane is released from its upper extreme position, its inertia tends to 25 carry it beyond the intermediate position and into such position that contact 12-12^a is momentarily closed, but this is prevented by the inertia of the counterweight device W-3-8. When the vane has been moved 30 to its lower extreme position and is released, it is returned to the intermediate position by the action of the counterweight device, whereupon screw 7 strikes base plate B and the force due to this device is removed. The 35 weight of the vane itself then operates to stop the vane before it swings far enough to close contact 11-11^a. It will be seen, therefore, that when the vane is released from either extreme position, momentary 40 closure of the opposite contact due to the tendency of the vane to swing beyond the intermediate position cannot occur, and that this result is attained without the use of 45 buffering means, and without the necessity for over-energizing the cores 14 and 14^a.

Although I have herein shown and described only one form of relay embodying my invention, it is understood that various changes and modifications may be made 50 therein within the scope of the appended claims without departing from the spirit and scope of my invention.

Having thus described my invention, what I claim is:

55 1. A relay comprising a member mounted to move in opposite directions from an intermediate position to two extreme positions and biased to move to one of said extreme positions, counterweighting means for holding said member in said intermediate position in opposition to its bias and for returning it to said intermediate position when it has been moved to said one extreme position, the normal bias of said member being dependent upon to return the member from the

other extreme position to the intermediate position, means for moving said member to said one extreme position in opposition to said counterweighting means and to the other extreme position in opposition to the bias of the member, and contacts controlled by said member.

2. A relay comprising a member mounted to move in opposite directions from an intermediate position to two extreme positions, and biased by its own weight to move from one extreme position to the other extreme position, counterweighting means for returning said member from the said other extreme position to said intermediate position, the weight of said member being depended upon to return the member from the first extreme position to the intermediate position, means for moving said member from its intermediate position to said extreme positions in opposition to the biasing forces acting on the member, and contacts controlled by said member.

3. A relay comprising a member mounted to move in opposite directions from an intermediate position to two extreme positions, and biased by its own weight to move from one extreme position to the other extreme position, a counterweight for returning said member from the said other extreme position to said intermediate position, the weight of said member being depended upon to return the member from the first extreme position to the intermediate position, a lost motion connection between said counterweight and said member for permitting movement of the member to the first-mentioned extreme position without interference by said counterweight, means for moving said member to its extreme positions in opposition to the forces biasing it to the intermediate position, and contacts controlled by said member.

4. A relay comprising a member mounted to move in opposite directions from an intermediate position to two extreme positions, and biased by its own weight to move from one extreme position to the other extreme position, a counterweight, means interposed between said counterweight and said member for raising said counterweight when the member moves from its intermediate position to its said other extreme position, but for permitting movement of said member from its intermediate position to the first-mentioned extreme position without interference by said counterweight, the weight of said member being depended upon to return the member from the first-mentioned extreme position to the intermediate position, means for moving said member to its extreme positions in opposition to the forces biasing it to the intermediate position, and contacts controlled by said member.

5. A relay comprising a member mounted to move in opposite directions from an in-

termmediate position to two extreme positions, and biased by its own weight to move from one extreme position to the other extreme position, counterweighting means for returning said member from the said other extreme position to said intermediate position, the weight of said member being depended upon to return the member from the first-mentioned extreme position to the intermediate position, means for moving said member from its intermediate position to said extreme positions in opposition to the

biasing forces acting on the member, a contact closed by said member when the latter occupies one extreme position, and a second contact closed by said member when the latter occupies the other extreme position. 15

In testimony whereof I affix my signature in presence of two witnesses.

ROBERT M. GILSON.
